STEERING WHEEL CIGARETTE CASE

Harold P. Blay and Fred G. Thannhauser, Detroit, Mich., assignors to Chrysler Corporation, Highland Park, Mich., a corporation of Delaware

Application August 26, 1942, Serial No. 456,166

3 Claims. (Cl. 206—19.5)

My present invention comprises a cigarette dispensing device for an automotive vehicle, the device being designed and arranged to facilitate withdrawal of a cigarette therefrom without distracting the attention of the operator from his duties as a driver. The primary object of the present invention is to promote safe driving and afford a greater degree of safety to drivers and pedestrians alike.

The present invention comprises a cigarette dispensing device adapted to be mounted centrally of the steering wheel so as to be within the operator's range of vision, without being so located as to interfere with the operator's line of sight to the road, the device comprising means to project a cigarette upward toward the operator's line of vision to the road. The position of the cigarette partially ejected from the device is such as to be readily visible to the operator without taking his eyes from the road.

A further object of the present invention is to provide a cigarette dispensing device comprising a holder adapted to retain a plurality of cigarettes, feeding mechanism adapted to place the cigarettes singly in position to be ejected, and an ejecting device adapted to eject a single cigarette partially from the holder so as to be within the reach of the operator.

A further object of the present invention is to provide a cigarette dispensing device comprising a holder which may be easily filled with a plurality of cigarettes.

A further object of the present invention is to provide a conveniently accessible cigarette dispensing device which will occupy an inconspicuous location, not mar the artistic arrangement of the vehicle, and be available as an optional accessory to a standard automotive vehicle.

These and other objects and advantages of the present invention will be readily understood by reference to the following specification and accompanying drawings wherein like numerals refer to like parts throughout.

In the drawings,

Fig. 1 discloses a view in side elevation of a conventional steering wheel and a portion of the steering wheel post of an automotive vehicle, the remainder of the vehicle not being illustrated as the position of a steering wheel within a vehicle is at present so standardized as to require no further illustration;

Fig. 2 is a full view on an enlarged scale of the steering wheel and dispensing device taken in the projection of the arrows 2—2 of Fig. 1;

Fig. 3 is an enlarged sectional view taken substantially along line 3—3 of Fig. 2;

Fig. 4 is a further sectional view taken along line 4—4 of Fig. 2;

Fig. 5 is a further sectional view taken along line 5—5 of Fig. 2;

Fig. 6 is an irregular sectional view taken substantially along line 6—6 of Fig. 2;

Fig. 7 is a view in perspective of the cigarette dispensing device separated from the steering wheel; and

Fig. 8 is a partial sectional view of the dispensing device showing means for latching the feeding mechanism to facilitate loading of the device with cigarettes.

Figs. 1 and 2 disclose a steering wheel comprising a rim 10 mounted on a pair of arms 11 extending from a hub 12 associated with a steering post 13. The steering wheel is shown in the position it occupies in an automotive vehicle so as to be in front of and within the normal field of vision of the operator with the hub 12 below the operator's line of sight to the road. When the wheel is centered the arms 11 lie in a substantially horizontal plane, as illustrated in Fig.

20, so as not to interfere with the operator's line of sight to the road, the only possible interference being that occasioned by a small portion of the rim 10. The wheel is illustrated as being provided with a horn ring 14 held in place by a mounting plate 15 extending across the top of the hub, and secured by screws 16 to the arms 11. The ring has extensions 17 extending beneath the arms 11 which are fastened to the contact plate 18 extending across the top of the hub of the wheel. Pressure at any point on the ring 14 causes contact to be made in the horn circuit through means not fully illustrated herein as such means are not a part of the present invention. It is to be appreciated that the plate 15 provides a mounting surface for the dispenser of the present invention, which plate may be replaced by a conventional, solid plate mounted upon the arms 11 if the dispenser is not desired.

The device of the present invention comprises an ornamental cover plate 20 of substantially greater width than height so as to lie along the arms 11 on top of the plate 15. The plate 20 is provided with a cavity within which the holder 21 of the cigarette dispensing device is positioned. The holder 21 comprises a front wall 22 which is provided with countersunk openings through which screws 23 may be passed to fasten the holder to the cover plate 20. A hinge 24 extends along the upper edge of the plate 20, one arm of the hinge being fastened to the holder 21 and the other arm of the hinge being fastened to the upper edge of the mounting plate 15 by means of countersunk screws 25. The lower edge of the holder 21 carries a spring catch device 26 adapted to snap into a catch retainer 27 mounted in the lower edge of the plate 15. A projection 28 adjacent the spring catch provides means whereby pressure may be applied to the lower edge of cover 20 to release the spring catch and permit the cover 20 with

the holder 21 attached thereto to be swung upwardly about the hinge 24 to expose the rear wall 29 of the holder 21. The rear wall 29 of the holder 21 is partially cut away centrally thereof, as shown in Fig. 7, so as to facilitate insertion of the cigarettes and it is provided with a transverse slot 29' through which cigarettes may be inserted in filling the holder as herein-after more clearly set forth. Access openings 30 are provided in the rear wall through which a screw driver may be inserted to apply the mounting screws 23.

The dispensing device comprises a spring-loaded feeding mechanism including a folded spring 35 retained between an end wall 36 of the holder and a channel shaped feeding bar 37. Two tabs 38 are struck outward from a portion of the bar 37 and extend through the open portion of the rear wall 29 so as to permit manual compression of the spring 35 toward the wall 36. The spring may be retained in compressed position by a retaining means comprising a spring catch 39 having one end fastened to the wall 36 by a rivet 40 which also retains the end of the spring 35 and its free end provided with a tongue 41 adapted to snap over a hook 42 struck upward from the wall of the feeding bar 37. When the spring has been compressed and retained in compressed position cigarettes may be placed in the holder by inserting the same downwardly through the slot 29' and moving then rightwardly, as viewed in Fig. 7, toward the right extremity of the holder. An ejecting opening 45 is provided in the upper edge of the cover plate 20 in registration with an opening 45' in the adjacent wall of the holder 21, for accommodating discharge of one cigarette at a time. When the holder has been filled the spring may be released by pressing inward on the exposed portion of the retainer 39. The wall 22 of the holder is provided with tracks 46 within which are guided tangs 47 struck outwardly from a portion of the feeder bar 37, the tracks and tangs serving to keep the feeder bar in alignment so as to slide freely lengthwise of the holder.

The outermost cigarette may be ejected from the holder by means of an ejecting device comprising a plunger 50 slidably mounted within an extension 51 at the lower right corner of the cover plate 20 and provided with a manual knob 52 within easy reach of the right hand of the operator. The plunger is held within the holder by a spring 53 compressed between the end wall of extension 51 and the enlarged head 54 of the plunger which is adapted to engage the end of a cigarette. The spring may be compressed by withdrawing the enlarged end 54 completely from the holder 21 through an opening 55 opposite the opening 45 through which the cigarettes are inserted and ejected. When the plunger is withdrawn the last cigarette is fed into axial alignment therewith by the feeding bar 37 so that retraction of the plunger by the action of spring 53 causes an end of the cigarette to be thrust upwardly toward the operator's line of sight to the road when the wheel is centered so that the cigarette may be readily seen without taking the eyes from the road.

It is also to be appreciated that modifications in arrangement and detail will be apparent to those skilled in the art without departing from the spirit of my invention. All such modifications as come within the scope of the following

claims are considered to be within the purview of my invention.

We claim:

1. In an automotive vehicle having a steering wheel comprising a hub portion and occupying a position within the vehicle operator's field of vision and rotatable about a central axis, a cigarette dispensing device mounted on said hub portion substantially centrally of said steering wheel so as to be within the operator's field of vision, said dispenser comprising a holder for a plurality of cigarettes, a manually operable ejecting device comprising a plunger reciprocable in a plane disposed transversely of said axis and adapted to propel a single cigarette upward in said plane from the dispenser toward the operator's line of sight to the road when the steering wheel is centered, and feeding mechanism adapted to feed cigarettes from the body of said holder into axial alignment with said plunger when said plunger is withdrawn preparatory to ejecting a cigarette.
2. In an automotive vehicle having a steering wheel occupying a position within the vehicle operator's field of vision, a cigarette dispensing device mounted substantially centrally of said steering wheel so as to be within the operator's field of vision, said dispenser comprising a holder for a plurality of cigarettes, a manually operable ejecting device comprising a plunger adapted to propel a single cigarette upward from the dispenser toward the operator's line of sight to the road when the steering wheel is centered, and feeding mechanism adapted to feed cigarettes from the body of said holder into axial alignment with said plunger when said plunger is withdrawn preparatory to ejecting a cigarette, said holder being hingedly mounted along one edge so that it may be swung away from its normal position to a loading position exposing its rear surface, the back wall of said holder being a partial wall only so that cigarettes therein may be contacted by the fingers to facilitate loading of the holder.
3. In an automotive vehicle having a steering wheel occupying a position within the vehicle operator's field of vision, a cigarette dispensing device mounted substantially centrally of said steering wheel so as to be within the operator's field of vision, said dispenser comprising a holder for a plurality of cigarettes, a manually operable ejecting device comprising a plunger adapted to propel a single cigarette upward from the dispenser toward the operator's line of sight to the road when the steering wheel is centered, and feeding mechanism adapted to feed cigarettes from the body of said holder into axial alignment with said plunger when said plunger is withdrawn preparatory to ejecting a cigarette.
4. In an automotive vehicle having a steering wheel occupying a position within the vehicle operator's field of vision, a cigarette dispensing device mounted substantially centrally of said steering wheel so as to be within the operator's field of vision, said dispenser comprising a holder for a plurality of cigarettes, a manually operable ejecting device comprising a plunger adapted to propel a single cigarette upward from the dispenser toward the operator's line of sight to the road when the steering wheel is centered, and feeding mechanism adapted to feed cigarettes from the body of said holder into axial alignment with said plunger when said plunger is withdrawn preparatory to ejecting a cigarette, said holder being adapted to hold the cigarettes in parallel, side-by-side alignment and said feeding mechanism comprising a folded spring compressible within the body of said holder between an end wall thereof and the cigarettes contained therein, said holder being hingedly mounted along one edge so that it may be swung away from its normal position to a loading position exposing its rear wall, and its rear wall being partially cut away to expose a portion of said spring whereby said spring may be compressed until said retainer is engaged.

FRED G. THANNHAUSER.
